UNITED STATES PATENT OFFICE.

CHARLES F. CUNO, OF MERIDEN, CONNECTICUT, ASSIGNOR TO THE CUNO ENGINEERING CORPORATION, OF MERIDEN, CONNECTICUT, A CORPORATION OF CONNECTICUT.

STARTING-SWITCH.

1,197,800.

Specification of Letters Patent. Patented Sept. 12, 1916.

Application filed December 27, 1915. Serial No. 68,625.

To all whom it may concern:

Be it known that I, CHARLES F. CUNO, a citizen of the United States of America, residing at Meriden, Connecticut, have invented a new and useful Starting-Switch, of which the following is a specification.

This invention relates particularly to switches for controlling the starting motors of automobiles, and the general objects of the invention are to improve and simplify switches of this character.

Further and special objects are to produce a switch for the general purposes set forth of high current carrying capacity which will be positive in action, compact in size, and which will be thoroughly protected both from a mechanical and electrical standpoint.

Other objects of the invention are to insure firm positive electrical engagement of the movable contact with the relatively stationary switch contacts and to protect the current carrying contact from injury by arcing and burning out.

In the accomplishment of the foregoing and other objects, I employ, in connection with the relatively stationary switch contacts, a movable spring pressed plunger carrying a main contact for bridging the switch contacts, and in addition, a supplementary contact for relieving the main contact of the arcing attendant upon breaking of the circuit. The main and supplementary contacts are preferably mounted so as to be self-adjusting on the plunger which supports them so as to accommodate themselves automatically to a proper engagement with the separated switch contacts.

The current carrying elements are all preferably inclosed in a waterproof casing and the entrance of moisture or foreign matter into this casing through the bearing of the operating plunger is guarded against by providing this plunger with a cap which slips over a hub carried by the casing and surrounding the plunger.

A special feature of the invention resides in the employment of the space between the plunger and the hub surrounding it as a housing for the spring which operates to withdraw the plunger from the contact making position.

Various other features and details of construction will appear as the specification proceeds, attention being directed to the accompanying drawings which illustrate a

practical and preferred form of the invention.

In these drawings: Figure 1 is a view in side elevation illustrating a switch embodying the invention mounted in a customary position in the floor of an automobile for operation by the heel of the driver. Fig. 2 is a vertical sectional view of the same. Fig. 3 is a sectional view taken through the lower portion of the switch casing substantially on the plane of the line 3-3 of Fig. 4. Fig. 4 is a top plan view of the lower member of the switch casing. Fig. 5 is a bottom plan view of the upper member of the switch housing showing the main and supplementary contacts on the lower end of the operating plunger. Fig. 6 is a bottom plan view of the lower part of the switch housing, the relatively stationary switch contacts having been removed in this figure. Fig. 7 is a broken sectional view illustrating the operation of the main and supplementary contacts. Fig. 8 is a drop perspective view of the main and supplementary contacts and the elements for mounting the same.

In Fig. 1 the invention is shown employed as a "heel switch," it being for this purpose mounted in the floor board 10 of an automobile with the operating stem or plunger 11 thereof disposed in position to be conveniently engaged by the heel of the driver. The switch is, in such a case, conveniently secured in place by bolts 12 passed through openings 13 in the flange of the switch casing, said bolts engaging at the upper side of the floor with a suitable face plate or escutcheon 14.

The switch parts are housed in a casing consisting in the present disclosure of a cupped base or lower portion 15, and a top plate 16, said parts being suitably fastened together, as by means of screws 9 engaged in the abutting flanges 17 and 18 of said two parts, a gasket 19 preferably being interposed between these flanges to make the casing water-tight and dust-proof.

The relatively stationary switch contacts are designated 20 and 21, these contacts being mounted in the base portion of the housing on a suitable insulating base 22. The means shown for securing these switch contacts in place are the screws 23 passed up through the bottom of the housing into engagement with the contacts, said screws being insulated from the casing by suitable

means such as insulating bushings or washers 24.

The switch contacts are made sufficiently massive to carry the relatively heavy current, which motor starting switches of this character are ordinarily called upon to transmit, and to gain the necessary contact surface the contact faces of such members are preferably made semi-circular in form, as 10 most clearly indicated in Fig. 4. These two semi-circular contacts are electrically separated from each other, in the present instance, by means of an insulating air gap 25. Attachment of the circuit connections is usually 15 made to the switch contacts through the medium of binding screws 26, said screws serving to clamp the terminal lugs 27 on the ends of the circuit connections direct to the lugs or extensions 28 of the contact members 20 which project downwardly through an opening 29 in the bottom of the switch housing. The movable switch contacts which serve to bridge the relatively stationary contacts are carried by the rod or plunger 11 guided 25 in the hub extension 31 of the top plate 16, said plunger being normally held in its uppermost position by means of a spring 32 seated in a recess 33 in the hub surrounding the plunger, bearing at its inner end against 30 the inner end of said recess and at the outer end against a shoulder on the plunger. The shoulder on the outer end of the plunger is provided in the present disclosure by a cap 34 secured to the outer end of the plunger 35 and having a dependent flange which slides over and makes a close joint with the reduced portion 35 at the outer end of the hub. This makes a sliding joint which excludes moisture, dust and other foreign matter, 40 and the shoulder 36 at the inner end of the reduced hub portion serves as a stop when engaged by the dependent flange of the cap 34 to limit the inward movement of the plunger. It will be seen further that this 45 particular form of joint will serve to shed any dirt that may be deposited on the top of the plunger from the heel of the operator's foot. The engagement of the underside of the cap with the end of the hub at 37, 50 may also serve as a stop to limit the movement of the plunger.

The primary or main bridging contact is designated 38, and the auxiliary or protective contact is designated 39. These contacts are preferably in the form of disks, 55 and a successive engagement of these contacts with the relatively stationary contacts is provided for by mounting the auxiliary contact on the plunger stem in advance of the main contact and by stepping the relatively stationary contacts, providing a seat 40 for the supplementary contact located below and in advance of the seat 41 for the main contact, the supplementary contact disk being of smaller diameter than the

main contact, so as to pass within the main contact seat 41 without engaging the same.

The main bridging contact may be slotted as indicated at 43 to provide a plurality of spring fingers, and may be dished downwardly somewhat as indicated in Fig. 2 to cause said spring fingers to engage the contact surfaces with a yielding wiping action. This main spring contact plate may be backed up by a reinforcing plate or disk 44. 75

The auxiliary contact may simply be in the form of a plain metal disk as indicated, in which case it is preferably backed up by a spring washer 45 or like spring element.

The main and auxiliary contacts are 80 mounted in spaced relation upon the plunger, in the present instance by forming the lower end of the plunger with a reduced shouldered extension 47 on which there is placed first an insulating washer 48, then an insulating bushing 49 over which the backing plate 44, main contact disk 38, spring disk 45 and auxiliary contact disk 39 are successively engaged, an insulating washer 50 being applied at the lower end of this 90 assemblage and the whole being secured in place as by riveting the reduced end 51 of the plunger over a metallic holding washer 52.

The two contacts on the plunger are 95 spaced apart a greater distance than the stepped contact faces 40 and 41 on the relatively stationary contacts, so that as the plunger is depressed, the lowermost auxiliary contact will first be carried into contact making engagement with the lowermost contact face 40 and thereafter the main bridging contact will be carried into engagement with its seat 41. The yielding mounting for the contacts permits of the contacts adjusting themselves to any inequalities in the contact faces, thus insuring firm, positive electrical engagement. This yielding character of mounting, together 100 with the backing plate 44 protects the contacts against injury by any undue pressure on the operating stem or plunger, and injury of this character is further positively guarded against by the limiting of the plunger movement through the engagement of the protective cap 34 with the stop shoulders 36 or 37 or the end of the plunger with the switch base at 53. When pressure on the plunger is released, the restoring spring lifts the plunger, and by reason of the special relation of parts described, separates the main contact from engagement with its contact seat 41, as indicated in Fig. 7. The final break of the circuit is thus carried by the supplementary contact and the main current carrying contact is thus wholly protected from injury by arcing, etc. 115

It will be seen from the foregoing that my invention provides a switch of extremely simple and compact design, and which while 120

suited to the rough service to which such switches are usually subjected, is capable of carrying a high current load without injury.

What I claim is:

- 5 1. In a switch of the character described, the combination of a closed switch casing, a pair of contact plates mounted in spaced relation in said casing and insulated from each other, a plunger mounted in the casing and movable in a plane toward and away from said separated contact plates, a yielding bridging contact mounted on said plunger and adapted to be carried by said plunger into position bridging the separated contact plates, and a backing plate on said plunger at the back of the bridging contact thereon. 60
- 10 2. In a switch of the character described, a closed casing, substantially semi-circular contact plates mounted in spaced relation in the bottom of said casing and insulated from each other, said contact plates having upper substantially semi-circular contact faces and lower substantially semi-circular contact faces stepped down on a lower plane than the upper contact faces and within the boundary of the upper contact faces, a plunger mounted in the casing, a contact disk on the lower end of the plunger and of less diameter than the upper contact faces to thereby pass down in the movement of the plunger into engagement with the inner lower contact faces, and a contact disk on the plunger above the first contact disk and of larger diameter than said first contact disk to thereby engage the upper outer contact faces. 70
- 15 3. In a switch of the character described, a switch casing, relatively stationary contacts in said casing, a hub extension carried by said casing, a plunger guided in said hub extension, a bridging contact carried by said plunger for engagement with the relatively stationary contacts, said hub having a reduced upper end and a stop shoulder at the base of said reduced portion, a cap carried by the upper end of the plunger and having a dependent flange sliding over the reduced portion of the hub, the inward movement of said plunger being limited by the engagement of the lower edge of said dependent flange with the shoulder at the base of the reduced hub portion and a spring acting to thrust the plunger in an outward direction. 75
- 20 4. In a switch of the character described, a switch casing, switch contacts mounted in spaced relation in said casing and insulated from each other, a plunger mounted in the casing movable toward and away from said contacts, a contact disk mounted on said plunger and of a size to bridge the switch contacts, said disk being slotted radially to form the same into a plurality of spring contact fingers, and a relatively rigid supporting plate mounted on the plunger at the back of said slotted contact plate. 80
- 25 5. In a switch of the character described, a switch casing, switch contacts mounted in spaced relation in said casing and insulated from each other, a plunger mounted in the casing movable toward and away from said contacts, a contact disk mounted on said plunger and of a size to bridge the switch contacts, said disk being slotted radially to form the same into a plurality of spring contact fingers, and a relatively rigid supporting plate mounted on the plunger at the back of said slotted contact plate. 85
- 30 6. In a switch of the character described, a switch casing, switch contacts mounted in said casing, a plunger mounted in the casing having a movement toward and away from said contacts, a yielding bridging contact on said plunger, a supporting plate at the back of said yielding bridging contact, a supplementary bridging contact mounted on the plunger in advance of said first bridging contact, and a yielding spacing member between said first and second bridging contacts. 90
- 35 7. In a switch of the character described, a switch casing, separated switch contacts mounted therein, a spring pressed plunger mounted in the casing and movable toward and away from said contacts, yielding bridging contacts mounted on said plunger in spaced relation, and adapted to successively engage with the separated switch contacts and a stop positively limiting the movement of the plunger toward the separated switch contacts, to thereby protect the yielding bridging contacts from injury by undue pressure on the plunger. 100
- 40 8. In a switch of the character described, a switch casing, relatively stationary contacts in said casing, a hub extension carried by said casing, a plunger guided in said hub extension, a bridging contact carried by said plunger for engagement with the relatively stationary contacts, said hub having a reduced upper end and a stop shoulder at the base of said reduced portion, a cap carried by the upper end of the plunger and having a dependent flange sliding over the reduced portion of the hub, the inward movement of said plunger being limited by the engagement of the lower edge of said dependent flange with the shoulder at the base of the reduced hub portion and a spring acting to thrust the plunger in an outward direction. 105
- 45 9. In a switch of the character described, a switch casing, switch contacts mounted in spaced relation in said casing and insulated from each other, a plunger mounted in the casing movable toward and away from said contacts, a yielding bridging contact on said plunger, a supporting plate at the back of said yielding bridging contact, a supplementary bridging contact mounted on the plunger in advance of said first bridging contact, and a yielding spacing member between said first and second bridging contacts. 110

CHARLES F. CUNO.
